L. R. GOLLADAY
DISCONNECTING SWITCH

Filed Nov. 26, 1920

UNITED STATES PATENT OFFICE.

LAWRENCE R. GOLLADAY, OF WILKINSBURG, PENNSYLVANIA, ASSIGNOR TO WESTINGHOUSE ELECTRIC & MANUFACTURING COMPANY, A CORPORATION OF PENNSYLVANIA.

DISCONNECTING SWITCH.

Application filed November 26, 1920. Serial No. 426,356.

To all whom it may concern:

Be it known that I, LAWRENCE R. GOLLADAY, a citizen of the United States, and a resident of Wilkinsburg, in the county of 5 Allegheny and State of Pennsylvania, have invented a new and useful Improvement in Disconnecting Switches, of which the following is a specification.

My invention relates to disconnecting 10 switches and particularly to switches of the double-throw, knife-blade type.

An object of the invention is to provide 15 a disconnecting switch with a simple and effective locking mechanism whereby the switch may be retained in closed relation with the contact jaw member.

Another object of the invention is to provide a disconnecting switch of the double-throw type with locking mechanism that 20 shall be effective in locking the switch-blade in either of its operative positions.

A further object of the invention is to provide a switch mechanism having the 25 above characteristics wherein the release of the latching mechanism is occasioned by the switch-opening movement of the operating lever.

A further object of the invention is to 30 provide a disconnecting switch with an operating lever that shall serve as a protecting case for the more delicate members of the structure.

These and other objects that will be apparent throughout the further description of the 35 invention are attained in the switch mechanism hereinafter described and illustrated in the accompanying drawings, wherein:

Figure 1 is a side elevation of the improved disconnecting switch.

Fig. 2 is a side elevation of a fragment 40 of the switch mechanism showing the latching mechanism on an enlarged scale.

Fig. 3 is a plan view of the mechanism shown in Fig. 2.

Figs. 4 and 5 are fragmentary views 45 illustrating my invention in modified form.

Referring to the drawings, the apparatus includes a switch-blade member 4 that

is pivoted, by means of a bolt 5, to a pivot 50 jaw member 6 that is mounted upon an insulating pedestal 7. The blade member 4 may be turned about the pivot 5 into operative engagement with contact jaw members 8 and 9 that are mounted on insulating pedestals 11 and 12, respectively. These 55 pedestals are disposed on opposite sides of the pivot jaw member 6, and the contact jaw members 8 and 9 are alined with the blade members 4. It will be understood that the pedestals 7, 11 and 12 are mounted upon 60 a suitable support.

The contact jaw members are of the usual type employed in connection with knife-blade switches, the jaw members being formed of flat metal plates designed to 65 yieldingly embrace opposite sides of the switch blade and to establish a circuit through the blade members and the contact jaw members.

As shown in Fig. 1, the blade member 70 4 is in operative engagement with the contact member 8, in which position, a circuit is established between the feed terminal 13 that is conductively connected to the pivot jaw member 6 and the load terminal 14 75 that is connected to the contact jaw member 8.

When the blade member is moved into operative engagement with the contact jaw member 9, it occupies the position shown 80 in broken lines in Fig. 1, wherein the blade serves to connect the feed terminal and the second load terminal 15 that is conductively connected to the switch-contact jaw member 9.

An operating lever 16, having two integral web portions 17 that are spaced apart to receive the free end of the blade member, is pivoted thereto by means of a pivot pin 18. Spaces 19 are provided between the 90 web portions 17 and the opposite sides of the blade member for the purpose of confining portions of the latching members 21 and 22 that are pivoted upon a pin 23 carried by the end of the blade member.

The inner ends of the latches 21 and 22

extend at substantially right angles from the main arm of the latch members and constitute cam arms 24 and 25, respectively. Pins 26 and 27, that are mounted in the web portion 17, respectively engage the cam arms 24 and 25, and it will be seen that, when the operating member 16, Fig. 2, is moved outwardly in an effort to dislodge the switch blade 4, it will first turn about the pivot pin 18 and cause outward movement of the cam arm 24 and movement of the latch member 21 to the left.

The latch members 21 and 22 are provided with enlarged end portions 28 and 29, respectively, having latch faces 31 and inclined cam faces 32. The latch members are normally retained in the positions indicated in Figs. 1 and 2 by means of short helical compression springs 33 that are disposed in the spaces 19 at points between the latching members and the web portions 17.

Outward movement of the latching members is limited by the engagement of the cam arms 24 and 25 with their respective pins 26 and 27. It will be understood that leaf springs may be substituted for the helical springs illustrated, and that it may be desirable to support the springs on seats fixed to the blade member in a manner similar to that disclosed in Figs. 4 and 5, which will hereinafter be described.

Separate stationary locking members 34 and 35 are disposed adjacent to the contact members 9 and 8, respectively. The locking members are provided with latching faces 36 and the cam faces 37. As shown, the locking members are mounted on the load terminals 14 and 15. Assuming the blade members to be in the positions shown in full lines in Fig. 1, the operation of the switch is as follows: A "hook stick" or other suitable implement is inserted in the opening 38 provided in the lever 16 and the lever is turned outward about the pivot pin 18, the extent of movement thereof with respect to the switch blade member being limited by engagement of the stop face 39 of the lever 16 with the end 41 of the switch-blade member.

Turning movement of the lever 16, with respect to the switch-blade member, causes the pin 27 to move the cam arm 25 of the latch member 22, and, consequently, the latch member 22 out of engagement with the locking member 35. When the latch is released, the blade may be disengaged from the contact jaw members by further outward movement of the lever 19.

When the blade is moved into engagement with the contact jaw members 9, the cam surface 32 on the latch 21 engages the cam surface 37 on the locking member 34, causing sufficient displacement of the latch member to permit the latch face 31 on the latch member 21 to slip behind the latch face 36 on the locking member 34. The spring 33,

therefore, serves to yieldingly retain the latch 21 in operative relation with its respective locking member.

When the lever 16 is again pulled outwardly by means of a "hook stick", the pin 26 will move the latch member 21 out of engagement with the locking member 34, after which operation, the switch may be returned to its original position. The cam surfaces 32 and 37 on the latch member 22 and the locking member 35, respectively, cooperate to displace the latch member to permit of its entrance to locking position with the locking member 35, in the manner previously described.

It will be seen from the foregoing that the latching members and springs are protected from contact with external objects by the operating lever 16, and that the construction is simple and inexpensive to manufacture. It is obvious that, while I have described the device as applied to a double-throw disconnecting switch, the latch mechanism may be applied to single-throw switches of various types.

Referring to Figs. 4 and 5, a modified form of the device is illustrated, wherein the latch members 21 and 22 are yieldingly retained in operative positions by means of helical springs 33 that are disposed between the latch members 21 and 22 and brackets 42 and 43, respectively, that are secured to the blade 4. These springs, as well as the springs 33 illustrated in Figs. 1 to 3, serve to center the latch members 21 and 22 and the operating lever 16.

While I have described and illustrated but two embodiments of my invention, it will be apparent to those skilled in the art that various changes, modifications, substitutions, additions and omissions may be made in the apparatus illustrated without departing from the spirit and scope of the invention, as set forth in the appended claims.

I claim as my invention:

1. Switch mechanism comprising a switch blade member movable into engagement with separate contact members, a stationary member adjacent each contact member, a separate latch member for each stationary member, pivotally mounted on opposite sides of the switch blade member and movable to locking engagement with its respective stationary member, yielding members normally holding the said latch members in operative position, and a single operating member carried by the switch member having means thereon for releasing the latch members, the said yielding members being interposed between the operating member and the latch members.

2. A switch mechanism comprising a switch blade, separate latch members mounted on opposite sides of the blade adjacent the end thereof and movable to locking

engagement with separate locking members, an operating lever fitting over the end of the blade and enclosing the pivoted ends of the latch members, the said lever being pivoted to the blade and having means thereon for releasing the said locking means, and spring members disposed between the operat-

ing lever and the latch members for yieldingly retaining them in locking engagement with the locking members. 10

In testimony whereof, I have hereunto subscribed my name this 18th day of November 1920.

LAWRENCE R. GOLLADAY.
